CHILD'S SLIPPER

Curt A. Renz, Chicago, Ill.

Application January 6, 1947, Serial No. 135,959

Term of patent 3½ years

(Cl. D7—7)

To all whom it may concern:

Be it known that I, Curt A. Renz, a citizen of the United States, residing at Chicago, in the county of Cook and State of Illinois, have invented a new, original, and ornamental Design for a Child's Slipper, of which the following is a specification, reference being had to the accompanying drawing, forming part thereof.

The figure is a front perspective view of a child's slipper showing my new design.

My design for a child's slipper of the type shown is characterized by the manner in which the vamp portion is ornamented by a representation of elephant ears on the sides and the trunk attached to the sole in a manner as shown.

I claim:

The ornamental design for a child's slipper, substantially as shown and described.

CURT A. RENZ.
